UNITED STATES PATENT OFFICE.

RAYMOND N. EHRHART, OF EDGEWOOD PARK, PENNSYLVANIA, ASSIGNOR TO WESTINGHOUSE ELECTRIC & MANUFACTURING CO., A CORPORATION OF PENNSYLVANIA.

MARINE TURBINE INSTALLATION.

1,343,665.

Specification of Letters Patent. Patented June 15, 1920.

Application filed October 18, 1917. Serial No. 197,361.

To all whom it may concern:

Be it known that I, RAYMOND N. EHRHART, a citizen of the United States, and a resident of Edgewood Park, in the county 5 of Allegheny and State of Pennsylvania, have made a new and useful Invention in Marine Turbine Installation, of which the following is a specification.

This invention relates to turbine installations and has for an object to produce a new and improved arrangement of turbine and condenser which is especially adapted to be employed on ships.

A further object of my invention is to 15 produce a marine turbine installation which is more compact and efficient than other similar installations now in use and known to me.

A further object is to produce a geared 20 turbine installation in which new and improved means are employed for mounting the turbine and condenser so that space is conserved and the condenser shell is free to expand and contract without affecting the 25 operation of the turbine.

These and other objects are attained by 30 means of a turbine installation embodying the features herein described and illustrated in the drawings accompanying and forming a part hereof.

My invention contemplates a compact power developing installation in which the turbine is mounted directly on the condenser and the latter is hung or supported from 35 above so that it is free to expand downward without affecting the alinement of the turbine. With such an arrangement the expansion joint between the turbine and condenser is eliminated and the length of the exhaust 40 passages is reduced to a minimum and only one joint is necessary in the connection between the turbine and the condenser. In geared installations the driving pinion of the gearing is preferably placed above the 45 driven gear so that the turbine, which is of course alined with the pinion, is elevated sufficiently to provide sufficient space for the condenser beneath the turbine. This makes a compact and effective geared unit.

50 In the drawings: Figure 1 is a somewhat diagrammatic side elevation of a geared marine turbine installation embodying my invention.

Fig. 2 is a diagrammatic end view of the apparatus illustrated in Fig. 1.

The apparatus illustrated includes a turbine 5, a condenser 6 located below the turbine and into which the turbine 5 exhausts, and a reduction gearing 7 located astern the turbine and the condenser, and operatively 60 connecting the turbine 5 to a propeller shaft 8. As shown, the installation is located in the hull 9 of a ship, a portion only of the hull structure being shown.

The turbine 5 is shown mounted directly 65 on and supported by the condenser 6. The latter is suspended from a structural frame 10, or in any other suitable manner, so that the points of support are substantially in the plane of the connection between the turbine 70 and the condenser. Under such condition the condenser forms a rigid and immobile support for the turbine, whereas the condenser shell, hanging below the condenser support, is free to expand and contract with 75 changes of temperature.

As shown, the turbine 5 occupies a position considerably above the propeller shaft 8, consequently the gearing 7 is arranged with the pinion above the gear so that the 80 pinion shaft 11 is in alinement with the rotor of the turbine 5.

The installation illustrated is unusually compact and simple as it is only necessary to properly suspend the condenser and to then 85 mount the turbine directly on it. A separate foundation or support for the turbine is therefore unnecessary, the connections between the turbine and the condenser are short, with but one simple connecting joint, 90 and the amount of space required for the installation is reduced to a minimum.

While I have described and illustrated but one embodiment of my invention, it will be apparent to those skilled in the art that 95 various changes, modifications, additions and omissions may be made in the apparatus illustrated without departing from the spirit and scope of the invention as set forth by the appended claim.

100

What I claim is:

A turbine installation comprising a condenser provided with a supporting exhaust connection for the turbine, a turbine supported by the said exhaust connection and 105 exhausting therethrough into the condenser,

and means for supporting the condenser so that the points of support are substantially in the plane of the joint between the connection and the turbine casing and so that the condenser and the turbine casing are free to expand independently on opposite sides of the point of support.

In testimony whereof I have hereunto subscribed my name this 17th day of October, 1917.

RAYMOND N. EHRHART.

Witness:

C. W. McGHEE.
